CONTROL DEVICE

Albert G. Hann, Detroit, Mich., assignor to Detroit Lubricator Company, Detroit, Mich., a corporation of Michigan

Application January 29, 1935, Serial No. 3,905

17 Claims. (Cl. 137—68)

My invention relates to control devices and more particularly to devices for controlling the flow of liquid.

One of the objects of my invention is to provide a new and improved gravity feed control device for controlling the flow of liquid.

Another object of my invention is to provide a device for controlling the flow of liquid, operable among other uses for controlling the flow of oil by gravity from a reservoir tank to an oil burner, and to provide a control device for this purpose having a new and improved arrangement of the operating parts thereof.

The invention consists in the improved construction and combination of parts, to be more fully described hereinafter and the novelty of which will be particularly pointed out and distinctly claimed.

In the accompanying drawings, to be taken as a part of this specification, I have fully and clearly illustrated a preferred embodiment of my invention, in which drawings—

Figure 1 is a view shown in side elevation of an oil burning apparatus employing my improved control device with a gravity feed system;

Fig. 2 is a top plan view of the control device with its cover removed to show the arrangement of the operating parts thereof;

Fig. 3 is a side view shown in cross-section taken along the line 3—3 of Fig. 2;

Fig. 4 is a top plan view of the control device with the cover in place;

Fig. 5 is a detail view of an oil strainer shown removed from the casing and embodying features of my invention;

Fig. 6 is a side view shown in cross-section taken along the line 6—6 of Fig. 2;

Fig. 7 is a fragmentary end view partly broken away and in section to show the outlet valve structure embodying features of my invention;

Fig. 8 is a fragmentary view shown in cross-section similar to Fig. 7, showing the valve in another position, and

Fig. 9 is a fragmentary view of the inlet valve structure shown in cross-section taken along the line 9—9 of Fig. 3.

Referring to the drawings, and more particularly to Fig. 1, there is shown my control device, designated in general by the numeral 1, having among other uses the controlling of the flow of oil by gravity from a reservoir tank 2 to an oil burning furnace 3. The control device is in communication with the oil burner through the conduit or pipe 3a. The control device is ar-

ranged in the oil line between the tank 2 and the furnace 3 for maintaining a predetermined substantially constant flow of oil to the burner, regardless of the quantity of oil in the tank, and this control device includes a substantially rectangular shaped casing 4 having a substantially rectangular shaped main chamber 5 in which the level of the oil or any other liquid is maintained at a predetermined substantially constant level by control mechanism arranged therein and hereafter described. A cover 6 is provided to close the chamber 5 and may be fixed to the casing 4 in any suitable manner, such as by the screws 8. The control device may be mounted, such as by the bracket 7, fixed to the furnace 10 wall, or in any other suitable manner so as to permit oil to flow preferably by gravity from chamber 5 to the oil burner.

In the casing and below chamber 5 there is provided a second chamber 10 into which the oil or other liquid first enters through passageway 11 and in which chamber it is filtered before entering chamber 5 through communicating passageway 12. The chamber 10 extends beneath chamber 5 substantially coextensive therewith and with the inlet port 11 located at one end in the bottom wall of the casing and with passageway 12 located in the other end of chamber 10. Preferably, the chamber 10 is in the form of a cylindrical bore having an opening 9 to receive a cylindrical shaped strainer 13. The strainer 13 may be formed of any suitable fine mesh wire, preferably having its inner end 15 closed such as by a cap 16 or other suitable closure member and having the outer end 17 open and provided with a tubular extension or collar 18.

In order to support the strainer within the chamber 10 and tightly seal the chamber against leakage and to do so in a manner so that the strainer may be readily assembled and/or disassembled with the chamber, I provide a closure member 19 slidably insertable in the chamber 10 with its inner end slidably telescoping the open end 17 of the strainer 13. The closure member 19 is preferably formed having a cylindrical shaped portion or shank 21 which slidably fits into the cylindrical bore or chamber 10 and extends part-way thereinto. The closure member 19 is provided with an external laterally extending flange 20 providing a shoulder for seating against the outer wall of the casing. Between the flange 20 and the wall of the casing, a washer or suitable packing material, indicated at 21a, may be provided to insure a tight leak-proof connection.

Besides serving as a closure member and support for the strainer 18, the closure member 19 also provides a means of obtaining communication between the inlet port 11 and the interior 5 of the strainer. To this end the closure member 19 is provided with longitudinally extending central bores 31 and 32, the larger bore 31 being located at the inner end of the closure member 19 thus providing when in operable position, an 10 internal and inwardly facing shoulder 33. The tubular extension or collar 18 of the strainer 13 slidably telescopes within the larger bore 31 of the closure member 19 extending part-way into the closure member and seating against the shoulder 15 33. Preferably a tight fit is desirable between the collar 18 and bore 31 to prevent the escape 20 of liquid therebetween and also to prevent accidental separation of the strainer and the closure member. To obtain such a fit, the collar 18 may be formed with a slightly larger external diameter than the diameter of bore 31 and be slit, as at 34, so that it can be slidably sprung fitted into the relatively small bore 31.

A portion of the shank 21 is formed intermediate its ends with an external reduced portion providing an annular slot 35 which cooperates with the inner wall of chamber 10 to provide an annular passageway 36. When the closure member is in position in the chamber 10, the annular passageway 36 is in alignment with the inlet port 11 of the casing and in open communication therewith. The inner central bore 32 extends from bore 31 only part-way into the shank, terminating at a point adjacent the annular slot 35 so that 35 radially disposed apertures or passageways 37 through shank 21 establish communication between the annular passageway 36 and the bore 32. Oil entering the inlet port 11 passes into the annular passageway 36 and then through radial 40 passageways 37 and bores 32 and 31 to the interior of the cylindrical strainer 13. After the oil is strained by flow through strainer 13 into chamber 10, it passes from chamber 10 to chamber 5 through passageway 12.

In order to securely fix the closure member 18 tightly against the casing and to do so in a manner so that the strainer may be easily assembled and/or disassembled without danger of tilting the casing and generally upsetting the normal function 45 of the control device commonly occurring when a wrench is applied to a threaded closure member, I provide a clamp or lever arm 22 arranged to extend across the flanged end of the closure member and having a portion intermediate its ends in contact with the closure member, the pressure applied to member 19 being applied 50 at the clamp ends either side of the closure member. In the present construction, the clamp 22 is L-shaped and hinged at one end to the casing at one side of the flange 20, as at 24, the other end 55 being provided with an aperture 25 for receiving a screw 26 or other suitable detachable holding means. The casing is also provided with a threaded aperture 26a positioned on the opposite side of member 19 for receiving the screw 26. Preferably the clamp is arranged so as to extend 60 across the flange 20 at the center thereof and is provided with a tapered protuberance 28 for engaging the member 19. The outer end of the closure member 19 is preferably provided with a 65 conical recess 29 for receiving the protuberance 28, thus obtaining a single point contact at the center of the closure member at which the pressure is brought to bear when the clamp 22 is drawn toward the casing by means of the screw 26.

By applying the clamping pressure at the end of the closure member and axially of the strainer bore by means of the screw 26 positioned off center, it will be readily understood that there is no tendency to move or tilt the device when tightening the screw 26.

As the strained oil enters the chamber 5 it is metered by a valve 40, operated by control mechanism within chamber 5 to maintain a predetermined substantially constant liquid level therein. 10 The valve structure, which is more clearly shown in Fig. 9, includes a fitting 41, having one end 42 externally threaded for threaded engagement with the internally threaded aperture of passageway 12. The fitting 41 extends vertically upward from the bottom wall of the casing and is provided with a central bore 44 in its upper end and a central bore 45 in its lower end in communication with bore 44 by means of a relatively smaller bore 46 providing an upward facing seat 47 and valve port for the valve 40. The valve 40 is preferably formed at its lower end with a substantially conical shaped portion 47a cooperable with the valve port to close the same. Laterally extending bores 48 through fitting 41 provide communication between bore 44 and the interior of chamber 5. The valve 40 which is reciprocable in the fitting has a vertically extending stem portion which extends part-way above the top of the fitting and to the upper end of which is rigidly fixed a collar 49. The upper end of the fitting 41 is provided with a guide member 50 preferably an apertured cap, sleeved over the end of the fitting.

A bracket 51, preferably substantially U-shaped, is rigidly clamped to the bottom wall of the casing by the fitting 41 which passes through an aperture in the base 52 of the bracket. The sides 54 of the U-shaped bracket extend upwardly on opposite sides of the fitting 41 and are connected at their upper ends by a horizontally extending bearing pin 56. Fulcrumed on the pin 56 there is a lever 57 bifurcated at one end to provide parallel arms 58 to receive the upper end of the valve member or collar 49 and which extend between the substantially horizontal flanges of the collar 49. The other end of the lever 57 has a float 60 rigidly fixed thereto, the float preferably being sufficiently heavy so that it normally floats with the greater portion thereof submerged.

The float 60 is preferably a relatively large cylindrical member of shallow depth having a horizontal area extending over substantially one entire end portion of the chamber 5. The valve 40, operated by the float, is located in the opposite end of the chamber 5 from float 60 thus permitting a long lever arm 57 between the large float 60 and the fulcrum point. Normally a relatively large float having a good leverage will efficiently operate to close tightly the valve 40 against relatively high oil head pressure when the liquid level in the chamber 5 rises to the predetermined substantially constant level.

In order to be sure that the valve 40 will close when the liquid level rises above the predetermined constant level and which the float 60 might fail to do because of grease or other foreign matter collected between the valve and the valve seat, I provide a safety device or second valve actuating device which is also disposed within chamber 5. This second valve actuating means includes a 70 toggle device normally inactive but arranged so as to have a potential force which when released operates to close the valve with such force as to crush out all foreign matter between the valve and its seat. The releasing of the toggle device is

controlled by a second float 62 relatively small compared to float 60, which smaller float is also disposed in chamber 5 and arranged so as to be sensitive to the rise in the liquid level above the 5 predetermined constant level.

The toggle device comprises in general a bearing member or support 63, a lever 64 and a coil spring 65 held in compression between the bearing member 63 and lever 64. The toggle device 10 is arranged at the top of the chamber 5 with the lever member 64 extending over the end of the vertically extending valve 40, for operating the same when released. The lever arm 64 may be formed of sheet metal, if desired, having a horizontally disposed portion 66 and preferably substantially vertically and longitudinally extending reenforcing side flanges 67 and 68. A downwardly extending portion or projection 70 may be provided on the underface of horizontally disposed 15 portion 66 of the lever 64 arranged for engagement with the top end of the valve 40 to reduce friction between the pivotable lever 64 and the reciprocating valve. The lever 64 is pivotally supported at one end, and adjacent the end wall 20 25 69 of the casing, the flanges 67 and 68 being provided with aligned slotted apertures running out at the ends for receiving a horizontal bearing pin 71. The spring 65 maintains the lever 64 in bearing engagement against the pin 71 and by reason 30 of this slotted bearing, it will be seen that the lever 64 can be readily removed by compressing the spring 65, after which the valve 40 can be lifted out of its housing thus facilitating assembly of the parts and rendering them easy to remove 35 to clean or repair or replace the same. The bearing pin 71 is arranged adjacent to the end wall 69 of the casing so that the lever 64 can be as long as possible to obtain good leverage, and this bearing pin 71 may be supported in the opposite casing side walls adjacent the end wall 69. To prevent side movement of the lever 64, it may be provided with a slot 73 to receive a vertical rib 74 integral with the casing wall 69 and which extends into the chamber 5. 40

45 By having the lever 64 pivoted at one of its ends and substantially at the extreme end of chamber 5 and by having the valve structure arranged in the same end of the chamber 5, it will be seen that the point of engagement of the lever 64 on the 50 valve 40 can be near the pivot point thus obtaining a relatively long lever arm on the other side of the contact point. The lever 64 extends from its pivot point preferably at a slight downward angle, or off center, with the flange 68 extending 55 the full length of the chamber 5 and projecting, as at 75, through a slotted aperture 76 in the opposite end wall 77 and extending externally thereof. The flange 67 and the horizontal portion 66 of the lever terminate within the chamber with the flange 67 extending slightly beyond the terminating point of the horizontal portion 66, as at 78. The pin or bearing member 63 is preferably rigidly fixed in the end wall 77 of the casing and in the same horizontal plane and in alignment 60 with the end 78 of the flange portion 67. The ends of the spring 65 may be provided with circular shaped bearing members 79 having central depressed recesses 79a for receiving the bearing members 63 and 78 which are preferably tapered or pointed, as shown in Fig. 3, thus having single point bearing engagement with the members 79 to permit ready movement of the lever 64 and reduce friction between the parts. 65

70 75 The arrangement of the toggle device having

the lever 64 inclined slightly downward or past center is the normal inactive position of the device, and because of this arrangement with the spring 65, the lever 64 has a potential force or tendency to pivot downwardly against the valve 5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

The second float 62 is also disposed in chamber 5 and is preferably pivotally connected to the other end of the lever 80, as at 86, for controlling the releasing of the toggle means. The float 62 is located in the opposite end of the chamber 5 from the pivot point of its lever 80 and at one side of the valve structure. This float has a horizontal area preferably relatively small compared to float 60 but having a relatively greater depth than float 60. A wall or partition means 87, which may be an integral part of the casing, as shown, surrounds the float 62 in close proximity thereto providing a chamber 88 which the float substantially fills. 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

In the present disclosure, the control device has two outlet valve structures for accommodating two burners, but since these valves are the same in structure and operation, a description of one is deemed sufficient. Referring to Figs. 7 and 8 in which views one of the valve structures is shown in detail, the valve structure is preferably located at one side of the casing and includes a valve chamber, the wall means 90 of which may be, as shown, an integral part of the casing, if desired. The wall means 90 extends vertically upward within the chamber 5, and the top portion 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

space 85 surrounding the valve stem and into which oil enters through an aperture 86 from chamber 5. Preferably the aperture 86 is in the form of a slot extending from the top of the wall 5 means 80 to a point adjacent the bottom wall of chamber 5. The relatively large bore 92 also extends to a point adjacent the bottom wall of chamber 5, at which point a relatively small bore 87 concentric with bore 92 provides an upwardly 10 facing seat 98 for the beveled face 99 of the valve. A bore 100 is provided which extends from the bottom wall of the casing to a point adjacent bore 87 and which may be threaded to receive a threaded closure plug 101. A relatively smaller 15 bore 103 serving as the valve port connects bores 87 and 100 and slidably receives the lower end portion of the valve which is diametrically reduced, as at 102, to slidably fit the same. Thus, 20 annular chambers 104 and 105, Fig. 8, are provided between the reduced diametrical portion 102 and the walls of the bores 87 and 100 respectively.

The valve stem is provided with a central longitudinally extending bore 106 which opens through the lower end of the reduced portion 102 and extends therefrom to a point well above the overflow level at which point it is in open communication through laterally extending apertures 107 with chamber 5 to permit the escape of gases which may form in the valve chamber and oil line. Bore 106 is in open communication with outlet port 108 through a laterally extending passageway 109, and extending vertically upward from the outlet port 108 and to a point above the constant liquid level is a passageway 111 through which gases forming in the valve chamber and oil line may also escape.

Preferably the lower end or reduced portion 102 of the valve has a tapered face and is provided 40 with a V-shaped opening 113 in the side thereof and in communication with bore 106 and also preferably converging upward from the bottom of the valve to an apex adjacent the conical portion 99 thereof. Oil enters chamber 85 through passageway 86 and when the valve is raised from its seat, as shown in Fig. 8, the oil enters annular chamber 104. The oil then passes through the V-shaped opening to the central bore 106 and then into chamber 105 from which it passes to 45 the outlet 108 through passageway 109. It will be seen that when the valve is raised from its seat and more of the V-shaped opening, below the apex, is in chamber 97, a larger quantity of oil will be permitted to pass to the outlet 108.

50 When the flame of an oil burner has been extinguished or the oil burner has been operating with a low flame, and a high flame is instantly desired, it is also necessary that a comparatively large quantity of oil must be instantly delivered to the burner. To this end I provide an outlet valve structure, the valve 94 of which is slidably disposed in its valve chamber so that it may be slidably withdrawn to immediately open the valve to maximum open position and also so that it can be employed as a pump plunger to pump oil to the burner. To accomplish this I provide cam means for vertically adjusting the valve 94 relative to its seat, and in the present structure the cam face is formed on the tubular-shaped top 55 edge of the valve chamber wall means, as at 114.

On the valve stem 94 and within chamber 5 is carried a cam follower 115, the follower shown being in the form of a tubular sleeve member having a central aperture for receiving the valve 70 stem 94. The follower 115 includes a down-

wardly extending portion or lug 118, the lower edge of which is in the same vertical plane as the cam face 114 for engagement therewith, and if desired the lug 118 may be an integral part of the wall of the sleeve member, as shown. A coil 5 spring 121 surrounds the valve stem 94 and is held under compression between the cam follower 115 and the underside of the cover 6 to resiliently maintain contact between the follower and the cam when they are in engagement and to urge the 10 valve against its seat 98 when the follower 115 and cam 114 are not in engagement. It will also be seen that upon closing rotation of the valve stem 94 the spring 121 aids to move the valve toward its seat. The slot 96 extending through 15 the upper end of the valve housing 90 provides a break or opening in the otherwise continuous cam face 114 and preferably the slot 96 is located relative to the cam face 114 so as to provide a space between the highest and lowest 20 points thereon. One side face of the slot 96 as indicated at 96a, Fig. 8, extends higher than the other and cooperates with the lug 118 to provide a stop. The cam 115 is preferably located at a point on the valve stem 94 such that when the lug 118 of the cam follower 115 is in engagement with the side edge of the slot 96, the valve will be seated or in closed position. In this position, the cam follower lug 118 overlies the slot 96 and accordingly is not in engagement with the cam face 25 114 so that the valve is free to seat and is aided to seat properly by the spring 121.

Upon rotating the valve stem 94 in one direction, the cam follower climbs the spiral cam, compressing the spring 121 and lifting the valve 94 away from its seat, thus opening the valve port 103 to permit an increase of the quantity of liquid flowing through outlet 108, whereas rotation in the opposite direction from closed position is prevented by engagement of the lug 118 with the side face 96a of slot 96. Preferably the vertical distance between the lowest point on the cam face 114 to the highest is such that when the lug 118 rests on the highest point of the cam, the valve is not in maximum open position, but is rather in a position to permit the largest quantity of oil flow to the burner and the resultant highest flame without danger of injury to the burner. It will be seen that the valve 94 by reason of the cam adjustment, can not be set in maximum open position, as is possible when a valve is threaded for adjusting it, for if the valve is rotated beyond the high point of the cam it will fall down to closed position. However, it is desirable when the burner flame has been extinguished or has been 50 operating at low or pilot flame to be able to open the valve to maximum open position, that is, to a position such that oil will flow unobstructed by the valve and be determined only by outlet port capacity, until such time as regular uniform flow through the oil line 3a is established. By reason of the use of a cam adjusting means, the valve 94 may be lifted without necessity of rotation and may be held away from its seat so that a maximum flow of oil will pass to the burner. It has also been found that gas bubbles form in the 55 control device passageways and in the pipe 3a leading to the burner when oil flow therethrough ceases or when only a small quantity of oil is flowing to the burner, and that these gas bubbles 60 interfere with the establishing of a uniform flow of oil to the burner when an increase in flow is desired. In addition, when the outlet valve is closed so that oil ceases to flow through pipe 3a or when only a small quantity of oil is passing 65 70 75 80 85 90 95 100 105 110 115 120 125 130 135 140 145 150 through pipe 3^a, air collects therein between the burner stand pipe and the outlet port 108 with the result that this air resists the passage of oil through the line 3^a when it is desired to obtain a high flame.

One of the advantages of the present valve outlet structure is that the valve 94 may be reciprocated as a pump plunger in its housing and agitate the oil in the line to the burner to dispel the gas bubbles formed therein and to aid the oil in pushing the air in line 3^a through to the burner. The gas from the bubbles that adhered to the wall of the portion of pipe 3^a that inclines downwardly from the burner will tend to rise to the burner and escape therethrough and will be aided in doing so by the increased volume of oil flow through pipe 3^a when the valve 94 is reciprocated, while the bubbles that adhered to the wall of pipe 3^a adjacent the control device 20 and those bubbles that adhered to the walls of the passageways of the control device casing, will tend to rise in passageways 101 and 106 and escape to the atmosphere above the level of the liquid in chamber 5.

25 The cover 6 is preferably formed with an upwardly extending tubular portion 122 concentric with the valve stem 94 and through which the valve stem extends and projects externally of the casing. A handle 120 is provided for manually operating the valve and may be fixed to the upper end of the valve stem 94, such as by a nut 121, or in any other suitable manner. The upwardly extending tubular member 122 is externally threaded for threaded engagement with a nut 123 and between the nut 123 and the top of the cover 6 is clamped a stop member 124 and a second stop member 125, the stop members having aligned apertures for receiving the tubular member 122. The handle 120 is formed with a 40 downwardly extending portion 127 for engaging the stop members 124 and 125. The stop members are preferably individual plate-like members having upturned portions for engagement by the downwardly extending handle portion 127.

45 The stop member 124, which may be termed the minimum stop member, is positioned such that when the handle portion 127 is in contact therewith the valve is opened sufficiently to permit a quantity of oil to flow to the burner sufficient to maintain a low flame or pilot light. The stop member 125, or maximum stop, is positioned such that when the handle portion 127 is in engagement therewith a desired maximum oil flow is permitted to pass to the burner. It will be understood that for different installations the desired positions of the stop members will vary so that an installation workman will position the stops in accordance with the conditions of a particular installation. If after the stops have been 50 properly positioned for a particular installation, the user should relocate the maximum stop in an effort to obtain a higher flame, it will be seen that the highest flame he could obtain would be when the stop 125 is positioned so that the valve may be rotated until the follower rests on the highest point of the cam 114 for beyond this, the cam follower 118 would drop down to closed position.

70 The minimum stop 124 is formed with an upwardly extending flange portion 128 which preferably extends to a point slightly above the lower end of the handle portion 127. To move the valve 94 to closed position, which position is shown in Figs. 3, 4, 6 and 7, the valve is first lifted until the lower end of the handle portion 127 clears the upwardly extending contact portion 128 of the mini-

mum stop 124 after which it may be rotated, in a clockwise direction as seen in Fig. 4, until it is beyond the contact member 128 after which it may be lowered and rotated until stopped by the engagement of the lug 118 with the side wall of slot 96. The maximum stop member 125 is provided with an upwardly extending flange 129 having a horizontally disposed portion 130 extending inwardly toward the valve stem 94 for engaging the downwardly extending portion 127 of the handle 120.

A complete operation of the control device is as follows: Oil is fed to the control device by gravity from the reservoir tank 2 and entering inlet port 11 passes through the radially disposed passageways 31 and then passes to the interior of the strainer 13. The strained oil passes through passageway 12 of the casing and into passageway 45 of the valve housing 41 and stands therein at the level of the valve seat 47, when the valve 40 is in closed position, by the force of gravity. Within the chamber 5, a desired constant liquid level is maintained by the valve 40 controlled by the float 60 which is pivotally connected to the valve and operable in response to changes in liquid level to reciprocate the valve 40 and accordingly open and close the same. When the valve raises to open the valve port, the oil standing in chamber 45 enters the chamber 5 through the laterally extending communicating bores 48. When the level of the oil in chamber 5 rises to the predetermined substantially constant level, the float 60 rises and closes the inlet valve port. If for some reason the float 60 failed to close the inlet valve port so that the level of the oil in chamber 5 rises above the predetermined constant level, the oil will overflow into the second chamber 88 over the dam 89.

When oil overflows into chamber 88, the float 62 therein is caused to rise in the chamber and upon doing so pivots the connecting lever 80 until it releases the toggle device including the lever 64, the toggle device then acting downwardly under force of the spring 65 to close the valve by the engagement of the lever 64 with the top of the valve stem 40. When this occurs, the remaining oil in chamber 5 external of chamber 88 is fed to the burner until exhausted after which the burner flame becomes extinguished. The user then knows that the safety valve actuating means has been tripped. By means of the lever arm 85 the float 62 can be reciprocated in its chamber and by reason of its close fit in the chamber, the overflow oil therein can be displaced by the float 62 and caused to flow back into chamber 5. By means of the lever portion 75 extending externally of the casing, the toggle device may be reset by lifting the handle 75 until the lug 84 again seats on the supporting latch 83 of lever 80. When the end 75 of lever 64 is raised, the lug 84 engages an inclined edge of the latch 82 and pivots lever 80 so that the latch moves in a counter-clockwise direction, as seen in Fig. 6, to permit the lug to be positioned on the latch edge 83. It will also be seen that the toggle device can be manually tripped by moving the lever arm 85 downwardly until the latch 82 is removed from beneath the lug 84. It will be understood that the rate at which oil enters the inlet port depends upon the rate at which oil is leaving the outlet port 108. When the handle 120 for manually operating the valve 94 is in the position shown, the valve is closed and the lug 118 of the cam follower 115 is in engagement with the stop 96^a. To open the valve port, the 75

valve 94 is first lifted by means of the handle 120 until it clears the minimum stop 128 and the valve 94 may then be rotated between the maximum and minimum stops. It will be understood that this construction provides for a positive shut-off for the burner at the control device.

From the foregoing description, it will now be seen that I have provided a new and improved control device for controlling the flow of liquid.

- 10 It will also be seen that I have provided a device of this character having a new and improved arrangement of the operating parts for increasing efficiency in operation of the device and that by reason of this new arrangement of the operating parts they may be compactly incased in a comparatively small casing. In addition I have provided novel means for attaching and sealing a removable strainer in position in the device and have also provided a novel outlet valve adjusting mechanism the advantages of which have been herein set forth.

It is to be understood that the use of the word "float" throughout the specification and claims is to be interpreted to include any body, counterbalanced or otherwise affected, for maintaining a predetermined substantially constant liquid level in the device, as well as floats of the type having a specific gravity less than the specific gravity of the liquid.

What I claim and desire to secure by Letters Patent of the United States is:

1. In a device of the character described, a casing having a chamber for liquid and a valve port therefor, a valve for controlling said port, a float operable in response to changes in liquid level for actuating said valve to maintain a substantially constant liquid level in the chamber, toggle means normally arranged past center and operable when released to move farther past center to actuate said valve, and a second float operable when the level of the liquid rises above said substantially constant level for releasing said toggle means.

2. In a device of the character described, a casing having a chamber for liquid and a valve port therefor, a valve for controlling said port and having a vertically extending stem portion, a float operable in response to changes in the liquid level for actuating said valve to maintain a substantially constant liquid level in said chamber, a second valve actuating means including a lever member within said chamber and having one end pivotally supported at one end of the chamber with the other end extending toward the opposite end of the chamber, said lever having a tendency to swing downwardly and engage said valve stem to close the valve port, a second lever within said chamber for normally supporting said first-named lever in spaced relation above said valve stem and having one end pivotally supported at one end of the chamber and in the opposite end from the pivot of said first-named lever, and a second float disposed in the end of the chamber adjacent the pivot point of the first-named lever and connected to the free end of the second-named lever, said second-named float being operable upon an increase in liquid level above said constant level to pivot said second-named lever to release the first-named lever.

- 70 3. In a device of the character described, a casing having a chamber for liquid and an inlet port therefor, a valve for controlling said inlet port and having a stem portion extending vertically upward therefrom, a float within said chamber operable in response to changes in liq-

uid level for actuating said valve to maintain a predetermined substantially constant liquid level, a second valve actuating means within said chamber including a lever normally disposed in spaced relation above said valve stem and operable when the level of the liquid rises above said predetermined substantially constant level for engaging and moving the valve to closed position, a second lever within said chamber having one end pivotally supported adjacent one end of said chamber and having a catch normally supporting said first-named lever and operable for releasing said lever when the level of the liquid rises above said predetermined constant level, wall means within said chamber providing a second chamber within the first and in communication therewith, a second float connected to the other end of said second-named lever and operable in said second-named chamber for releasing said first-named lever, end portions of adjacent ends of said levers extending externally of the casing for latching or unlatching said levers.

4. In a device of the character described, a casing having a chamber for liquid and an inlet port therefor, a valve for controlling said port and having a stem portion extending therefrom, means operable in response to changes in liquid level for actuating said valve to maintain a predetermined substantially constant liquid level in said chamber; a second valve actuating means responsive to predetermined increase of liquid level above said predetermined substantially constant level, a lever operable by said second actuating means, said lever overlying said valve and operable on said valve stem upon operation of said second actuating means thereby to move the valve to closed position, a pivot pin for said lever, said lever having a recessed bearing face running out to the edge of the lever for receiving said pin, and resilient means for maintaining the bearing face of said lever in engagement with the pin whereby said lever is removable for access to said valve.

5. In a device of the character described, a casing having a chamber for liquid and having an inlet thereto, a valve controlling said inlet, means cooperable with said valve to maintain the liquid level in said chamber substantially constant, said casing having a second chamber communicating above said constant level with said first-named chamber, a float member in said second-named chamber, safety means cooperable with and for moving said valve to closed position, said float member acting on said safety means upon overflow of liquid from said first-named chamber into said second-named chamber thereby to close said valve, manually operable means extending externally of said casing for resetting said safety means, and manually operable means extending externally of said casing and operable to actuate said safety means to close said valve.

6. In a device of the character described, a casing having a chamber for liquid and an inlet port therefor, a valve for controlling said inlet port, a float within said chamber operable in response to changes in liquid level for actuating said valve to maintain a predetermined substantially constant liquid level, a second valve actuating means within said chamber including a lever cooperable with said valve and operable when the level of the liquid rises above said predetermined substantially constant level for engaging and moving the valve to closed position, a second lever within said chamber having a catch normally supporting said first-named lever and operable for releasing

5 said lever when the level of the liquid rises above said predetermined constant level, a float connected to said second-named lever and operable upon increase of liquid level above said constant 5 level for releasing said first-named lever, end portions of said levers extending externally of the casing for latching or unlatching said levers.

7. In a device of the character described, a casing having a chamber for liquid and an inlet 10 port therefor, a valve for controlling said inlet port, a float within said chamber operable in response to changes in liquid level for actuating said valve to maintain a predetermined substantially constant liquid level, a second valve actuating means within said chamber including a lever cooperable with said valve and operable when the level of the liquid rises above said predetermined substantially constant level for engaging and moving the valve to closed position, 15 a second lever within said chamber having a catch normally supporting said first-named lever and operable for releasing said lever when the level of the liquid rises above said predetermined constant level, wall means within said chamber providing a second chamber within the first and in communication therewith, a float connected to 20 said second-named lever and operable in said second-named chamber for releasing said first-named lever, end portions of said levers extending externally of the casing for latching or unlatching said levers, the externally extending end portion of said second-named lever comprising manual means for actuating said second-named float whereby liquid may be returned from said 25 30 second-named chamber to said first-named chamber.

8. In a device of the character described, a casing having a chamber for liquid, an upward extending inlet member opening into said chamber and having a valve port, a valve member reciprocal in said inlet member and controlling said port, a float member in said chamber and operatively connected to said valve member to maintain a substantially constant liquid level in said chamber, safety means cooperable with said valve member and operable to move said valve member to closed position upon failure of said float member to maintain said constant level, said safety means comprising a lever in overlying relation to and engageable with said valve member, said lever being readily removable for access to said valve member, and a coil spring arranged with one end abutting the free end of said lever and holding said lever in engagement with its 55 fulcrum.

9. In a device of the character described, a casing having a chamber for liquid, an upward extending inlet member opening into said chamber and having a valve port, a valve member reciprocal in said inlet member and controlling said port, a float member in said chamber and operatively connected to said valve member to maintain a substantially constant liquid level in said chamber, safety means cooperable with said valve member and operable to move said valve member to closed position upon failure of said float member to maintain said constant level, said safety means comprising a lever in overlying relation to and engageable with said valve member, said lever being readily removable for access to said valve member, releasable means holding said lever in engagement with its fulcrum, and cooperable means on said lever and said casing to maintain said lever in overlying relation to 75 said valve member.

10. In a device of the character described, a casing having a chamber for liquid and having an inlet, a valve controlling said inlet, a float member in said chamber and operatively connected to said valve to maintain a substantially constant liquid level in said chamber, a safety float in said chamber and operable to close said valve upon failure of said float member to maintain said constant level, a normally inactive lever in said chamber and engageable with said valve, a spring urging said lever into engagement with said valve to close said inlet, an arm on said lever and positioned laterally of said spring and extending externally of said casing for manually resetting said lever, a second lever operable by 10 said safety float, cooperable latching means on said levers operable to hold said first-named lever in inactive position and operable by said safety float to release said first-named lever, and an arm on said second-named lever for manually releasing said latching means. 15 20

11. In a liquid level control device, a casing containing a chamber having an inlet, a valve controlling said inlet, a float responsive to liquid level in said chamber and operatively connected to said valve to maintain a substantially constant liquid level in said chamber, a safety float in said casing and operable upon predetermined increase of liquid level above said constant level, a lever in said casing engageable with said valve to close said inlet, said lever having an inactive position, a second lever cooperable with and operable to hold said first-named lever in said inactive position, said safety float acting upon its operation by increased liquid level to move 30 said second-named lever to release said first-named lever, said levers being manually movable relative to each other and into holding relation, and manually operable means projecting externally of said casing for disengaging said 40 levers whereby said first-named lever will move said valve to close said inlet and for also positioning said levers in holding relation. 35

12. In a liquid level control device, a casing containing a chamber having an inlet, a valve controlling said inlet, a float responsive to liquid level in said chamber and operatively connected to said valve to maintain a substantially constant liquid level in said chamber, a second chamber in said casing, a wall in said casing determining the maximum liquid level therein and separating said chambers, a safety float in said second chamber, a lever in said casing engageable with said valve to close said inlet, said lever having an inactive position, a second lever cooperable with 45 and operable to hold said first-named lever in said inactive position, said safety float acting upon overflow into said second-named chamber to move said second-named lever to release said first-named lever, said levers being manually movable relative to each other and into holding relation, and manually operable means projecting externally of said casing for disengaging said levers whereby said first-named lever will move said valve to close said inlet and for 50 also positioning said levers in holding relation. 55 60

13. In a control device having a liquid level responsive means for actuating a valve to maintain a substantially constant liquid level in a reservoir, a safety device for moving said valve to closed position upon failure of said responsive means to maintain said constant level comprising a lever member movable into engagement with said valve member, a spring under stress and exerting a force operable when released to 70 75

- move said valve to closed position, said spring extending in the same general direction as said lever and having one end in abutting engagement with the free end of said lever, the point of engagement of said spring and said lever being disposed pastcenter and being movable further pastcenter to move said lever to engage and move said valve to closed position, means holding said spring under stress with the point 5 of engagement between the spring and said lever in its first-named pastcenter position, and a liquid level responsive means operable upon a predetermined liquid level rise above said substantially constant level for actuating said holding 10 means to release the force exerted by said spring.

14. In a control device having a liquid level responsive means for actuating a valve to maintain a substantially constant liquid level in a reservoir, a safety device for moving said valve to closed position upon failure of said responsive means to maintain said constant level comprising a lever member overlying said valve member and movable to engage said valve member, spring means under stress and exerting a force tending and operable when released to pivot said lever to move said valve member to closed position, said lever member having a fulcrum support and being readily removable from its fulcrum to give access to said valve member, said lever member being held by said spring means against its fulcrum, and means operable in response to a predetermined liquid level increase above said constant level for releasing the force of said spring.

15. In a liquid level control device, a casing having a chamber for liquid and a valve port therefor, a valve for controlling said port, a float operable in response to changes in liquid level for actuating said valve to maintain a substantially constant liquid level in said chamber, a second valve actuating means and having an active and an inactive position, said second valve actuating means including an arm member having a portion extending exteriorly of said casing for manually positioning said second-named valve actuating means in its inactive position, a second chamber in communication with said first-named chamber and into which liquid flows upon predetermined liquid level increase above said substantially constant level, a float disposed in said second-named chamber operable in

response to liquid rising in said second-named chamber for controlling movement of said second-named valve actuating means to its active position, and an arm member associated with said float and having a portion extending exteriorly of said casing for moving said second-named float to displace and expel liquid from said second-named chamber, said arm member also having connection with said first-named arm member and operable to position said second-named valve actuating means in its active position. 10

16. In a liquid level control device, a casing having a chamber for liquid and a valve port therefor, a valve for controlling said port, means responsive to changes in liquid level in said chamber for actuating said valve to maintain a substantially constant liquid level in said chamber, toggle means normally arranged past center and operable when released to move further 20 past center to actuate said valve, means for holding said toggle means in said first-named past center position, and means operable in response to a predetermined increase in the liquid level above said substantially constant level to actuate 25 said holding means to release said toggle means.

17. In a control device having a liquid level responsive means for actuating a valve to maintain a substantially constant liquid level in a reservoir, a safety device for moving said valve to closed position upon predetermined increase in liquid level above said substantially constant level comprising, a movable member having a fulcrum, spring means having a fulcrum and held under stress between its fulcrum and said movable member, said spring means being operable on movement of said movable member in one direction to move the valve to closed position, the point of engagement between said 40 spring means and said movable member being disposed past center and being movable further past center on movement of said movable member by said spring means, means to hold said spring means under stress with the point 45 of engagement between said spring means and said movable member in said first-named past center position, and means operable on said predetermined increase in liquid level to actuate said holding means to release said spring means. 50

ALBERT G. HANN.
